[57] CLAIM

The ornamental design for a lift truck with driver's seat, as shown and described.

DESCRIPTION

FIG. 1 is a right side view of the lift truck with the driver's seat according to my novel design;

FIG. 2 is a left side view of the lift truck with the driver's seat according to my novel design;

FIG. 3 is a front view of the lift truck with the driver's seat according to my novel design;

FIG. 4 is a rear view of the lift truck with the driver's seat according to my novel design;

FIG. 5 is a top view of the lift truck with the driver's seat according to my novel design;

FIG. 6 is an enlarged view of the top, left portion of the lift truck with driver's seat shown fragmented for ease of illustration;

FIG. 7 is a front right perspective view of the lift truck with the driver's seat according to my novel design;

FIG. 8 is a front left perspective view of the lift truck with the driver's seat according to my novel design;

FIG. 9 is a right rear perspective view of the lift truck with the driver's seat according to my novel design; and,

FIG. 10 is a left rear perspective view of the lift truck with the driver's seat according to my novel design.
